C. A. WISSEL.

AUTOMATIC BRAKE FOR LAUNDRY WASHING MACHINES.

APPLICATION FILED JULY 17, 1914.

Patented Oct. 10, 1916.

UNITED STATES PATENT OFFICE.

CONRAD A. WISSEL, OF DAYTON, KENTUCKY.

AUTOMATIC BRAKE FOR LAUNDRY-WASHING MACHINES.

1,200,907.

Specification of Letters Patent.

Patented Oct. 10, 1916.

Application filed July 17, 1914. Serial No. 852,104.

To all whom it may concern:

Be it known that I, CONRAD A. WISSEL, a citizen of the United States, residing at Dayton, in the county of Campbell and the State of Kentucky, have invented a new and useful Automatic Brake for Laundry-Washing Machines, of which the following is a specification.

This invention relates to automatic band-clutch braking devices for use in checking or cushioning the momentum or velocity of reciprocally-rotating barrel clothes-washing machines when they are approaching the point of reversal in operation, whereby all heavy and wearing shocks and strains on the gearing and reversing apparatus are entirely avoided; and the invention consists in the provision of an impinging lateral flange or ring on the inner face of the adjacent drive-wheel, which flange is encircled and frictionally-engaged by a circular clutch-band, the spaced opposite ends of which band are secured to the outer free ends of pendent levers that are pivotally mounted in co-acting pairs on the face of the adjacent barrel-head.

The expenditure of power is reduced to a minimum in the use of the structure herein that is shown in the accompanying sheet of drawings, in which,—

Figure 1 is a front elevation of the device showing it mounted on a fragmentary portion of the head of a washing-machine barrel and as it appears when at rest; Fig. 2, a perspective view of the intervening, segmental toothed plate used for automatic cushioning or brake action in the reverse-motion of the barrel; Fig. 3, a perspective view showing the inner or rear face of one of the clutch-band actuating or tightening and releasing levers used in braking the washer-barrel; and Fig. 4, a perspective view showing the spring-controlled pawl seen in Fig. 3, but on a slightly larger scale.

1 indicates a fragmentary portion of one of the end-heads of a barrel washing-machine; 2 a small fragmentary portion of the adjacent driving spur-gear that is axially-attached to said end-head 1 (not shown herein); 3 a ring or circular flange that is provided with inwardly-projecting and perforated lugs 4, through which latter suitable bolts are passed and engaged with the spokes 5 of said driving spur-gear 2 so that the said ring 3 shall be properly coupled and travel with said gear; and 6 a clutch-

band encircling the ring 3 but normally free therefrom, as shown in Fig. 1, and whose opposite spaced ends 7, 7 are bent or turned upwardly and suitably orificed for the outer threaded-ends 8 of the forked levers or connecting-links 9, the latter being hereinafter properly referred to. The clutch-band 6 is provided with spaced lugs 10 to form a mounting-fork that is connected by means of a transverse bolt or rivet 11 (shown dotted in Fig. 1) with an orificed bracket-arm 12 that has lateral feet 13 to receive screws 14 whereby said clutch-band is held in place on the barrel-head 1.

15 indicates a base-plate secured by means of bolts 16 to the face of the barrel-head 1 in diametric-alinement with and above the said driving-gear 2.

17, 17 are lugs projecting forwardly from the lower opposite corners of said base-plate 15, the purpose of which will be hereinafter referred to.

18 indicates each one of a pair of pendent levers that are pivotally mounted at their upper ends on studs 19 that project forwardly from the face of the upper part of the base-plate 15, suitable cotters 20 being used to secure the levers 18 on said studs but free to swivel thereon.

21 indicates an upward extension from the top of each of the levers 18, between which extensions a spiral spring 22 is stretched, suitable screws 23 being used to secure the opposite ends of said spring in place and the spring acting to draw said upper extensions of the levers toward each other under tension and to thereby normally throw or spread the lower ends of said levers 18 apart or from each other, coacting teeth 24 and 25 at the arc of contact of the adjacent upper ends of said levers 18 being provided so that said levers act in unison when swung in either direction for the purpose of drawing the two ends of the clutch-band 6 toward each other in frictional or embracing relation with the ring 3 through the medium of the swinging coupling-links 9, hereinbefore referred to, or in spreading said ends of the clutch-band 6 apart for releasing said clutch-band from braking-contact with the said ring 3. The clutch-band 6 is preferably somewhat resili-ent so that it is normally disposed to expand outwardly away from contact with said ring 3, as customary in clutch-bands. The coupling-links 9 are secured to the opposite ends

100
105
110

of said clutch-band by means of nuts 26. These nuts 26 enable the proper adjustment of said levers 18 in connection with said clutch-band for the desired braking-action 5 of the latter.

27 indicates a rotatory segmental disk or plate that is mounted on the base-plate 15, the latter being provided with a stud 28 that is in axial-alinement with the gear 2 and, also, in diametric-alinement with the center of the end-head 1 of the barrel and the meshing-teeth 24 and 25 of the levers 18, as best shown in Fig. 1. The segmental-plate 27 is mounted on said stud 28 so as to 10 rotate thereon and is provided with outwardly-projecting lugs or pins 29, the latter being preferably of oblong double-convex form for the purpose hereinafter referred to. The segmental-plate 27 is also provided 15 with radial teeth or arms 30. An inwardly-disposed pin or lug 31 (shown in dotted-lines in Fig. 1) is provided on the inner face of the spoke 5 of the gear 2, at a point located at the outer end of said spoke 5 and 20 in position to engage the teeth 30 of the segmental-plate 27 for actuating said plate 27 intermittently when the washer-barrel is rotated in either direction and to bring said pins or lugs 29 on the outer face of said 25 plate 27 into engagement with cam-faced projections 32 provided on the pawls 33, the latter being pivotally-mounted on pins 34 that project from one end thereof and engage suitable openings or holes made in the 30 lower ends of said levers 18. The pawls 33 are held by means of contracting springs 35 under tension against lugs or stops 36 provided on the inner face of each of the said 35 levers 18. The stops 36 form rests for the said pawls when in normal position and, also, for the contacting-pressure of the pins 29 against the cam-formations 32 on said pawls 33 when said segmental-plate 27 is forced to rotate by the contact of pin 40 31 with either of the teeth 30 of said segmental-plate 27, during the time of forward-movement of the washer-barrel in either direction. The swinging of the pawls against the tension of their springs 35 away from 45 the stops 36 is provided for the reverse-movement of the said segmental-plate 27 when the other pin or lug 29 on said plate 27 is in engagement with the cam-formation 32 on the other lever 18 in drawing the two 50 levers together at their lower ends for bringing the clutch-band 6 into frictional engagement with the ring 3 to cushion the rotating-force of the washer-barrel at the close of a forward-movement thereof and ready for 55 the reverse-movement thereof when the said levers 18 are tripped apart by the release of their cam-formations 32, in turn, from contact with the pins or lugs 29 on the segmental-plate 27. The lugs 17 at the opposite 60 lower corners of the base-plate 15 form stops 65

to prevent the levers 18 spreading apart beyond their proper limit of movement in spreading the opposite ends of the clutch-band 6 apart. The spiral spring 22 that connects the upper ends of the levers 18 70 serves to spread the lower ends of the levers 18 apart after each compressing of the clutch-band 6 automatically.

The device is preferably timed in use so that the barrel or clothes-receptacle shall rotate twice before reversing, in order to obtain the best results in washing the clothes. In operation, the driving-gear 2 is rotated (in the direction of the arrow shown thereon) by the motor and brings the pin 31 on its inner face into contact with the next adjacent corner of the segmental-plate 27 for the first revolution of the clothes-receptacle and then again, on the next revolution, into contact with the next succeeding tooth 30 of said segmental-plate, the pins or lugs 29 on the back of the latter contacting with the inner concaved edges of the cam-faced projections 32 on the pawls 33 until the tips of the latter are reached and at which time the forward-movement of the barrel has been concluded ready for the reverse-movement. The contraction of the springs 35 now serves to immediately draw the pawls 33 into engagement with the stops 36 so that the pins 95 29 can be in frictional riding-contact with the outer convexed edges of the cam-faced projections 32, whereby the levers 18 are drawn toward each other at their lower ends to, in turn, draw the opposite ends of the 100 clutch-band 6 toward each other for the frictional braking-action of the said clutch-band on the ring 3 and gradually bringing the barrel to a stop ready for the said reverse-movement thereof. On the completion of 105 said forward-movement of the barrel the pins 29 turn the lower ends of the pawls 33 and then ride along the inner concaved edges of the latter whereby said pawls are forced outward again against the tension of the 110 springs 35 and the lower ends of said levers 18 simultaneously thrown apart by the contracting-action of the upper spring 22 that was held under expansion during the braking-action of the levers 18 and clutch-band 6. 115

I claim:—

A cushioning or braking device for reverse-acting rotatory, barrel clothes-washers comprising a clutch-band, a ring or flange provided on the driving-gear of the barrel and adapted to be frictionally-engaged by said clutch-band, an inwardly-projecting pin on said driving-gear, a base-plate on the barrel-head, a toothed segmental plate or rotatory disk on said base-plate, a pair of levers pivotally-mounted on said base-plate and connected at their lower ends to the opposite spaced ends of said clutch-band, means at the upper ends of said levers to automatically draw them toward each other so 125 130

that their lower ends shall spread apart after each compressing-action of said clutch-band, toothed means between two contacting-arcs at the upper ends of said levers, pins on said 5 segmental plate or disk, spring-controlled pawls on the inner face of the lower ends of said levers, and cam-formations on said pawls adapted to be engaged by said pins on the said segmental-plate whereby the levers 10 are brought together at their lower ends to draw the spaced ends of the clutch-band toward each other for the braking-operation

in the reverse-motion of the washer-barrel and, also, the spreading apart of said levers automatically to release the braking pressure 15 or contact for the free rotatory-movement of said washer-barrel.

In testimony whereof I have signed my name to this specification in presence of two witnesses.

CONRAD A. WISSEL.
